[57] CLAIM

The ornamental design for a spring clip, as shown and described.

DESCRIPTION

FIG. 1 is a top plan view of a spring clip showing my new design;

FIG. 2 is a front elevational view;

FIG. 3 is a bottom plan view;

FIG. 4 is a rear elevational view;

FIG. 5 is a right side elevational view, the left side being a mirror image thereof;

FIG. 6 is a cross-sectional view taken in the direction of arrows 6—6 in FIG. 2;

FIG. 7 is a top perspective view;

FIG. 8 is a top perspective view in an unclamped condition; and,

FIG. 9 is a top perspective view thereof, the fragmentary sheets of paper being depicted by means of broken lines for illustrative purposes only and forming no part of the claimed design.

FIG. 1**FIG. 5****FIG. 2****FIG. 6****FIG. 3****FIG. 7****FIG. 4****FIG. 8****FIG. 9**
